UNITED STATES PATENT OFFICE.

HARRY LITTLE, OF PLAINFIELD, NEW JERSEY, ASSIGNOR TO NILES-BEMENT-POND COMPANY, OF NEW YORK, N. Y., A CORPORATION OF NEW JERSEY.

MACHINE TOOL.

Application filed July 9, 1923. Serial No. 650,397.

This invention relates to tool operating mechanism for planers and like machines. Such machines ordinarily comprise a work table and one or a pair of uprights adjacent to the table. A cross rail is mounted on the uprights and tool heads may be supported on the cross rail and on the uprights beneath the rail. The first said heads are ordinarily termed the "rail heads" and the second said heads are ordinarily termed the "side heads". Specifically, my invention relates to mechanism for elevating and clamping the rail to the said upright or uprights and for feeding and traversing the tool heads. The primary object of the invention is to provide an improved mechanism for performing these functions.

More specifically, the invention provides an electric motor, preferably on the cross rail, and mechanism operated thereby for intermittently feeding the tool supports for continuously traversing the tool supports in either direction, and for moving the cross rail on the uprights. Mechanism, including a manually operable clamping shaft extending along the rail, is provided for clamping the rail to the uprights. Connections are also provided between the clamping shaft and the motor operated mechanism whereby the motor will be operatively connected to the tool supports when the rail is clamped and will be disconnected therefrom and operatively connected to the rail elevating mechanism when the rail is unclamped. One object of the invention is to provide a tool operating mechanism embodying these improved features.

The motor is adapted to feed and traverse the tool supports on both the cross rail and uprights of the machine and mechanism is provided on the cross rail in connection with the motor for so traversing all such tool supports and for feeding the same the desired amount. This mechanism, as illustrated in the drawings, comprises a shaft on the rail for operating each tool support. The connections to the motor provide for either continuously operating such shafts to traverse the tool supports or intermittently operating the shafts to feed the tool supports. All the tool supports are therefore operated and controlled from a single mechanism at the front side of the machine within easy reach of the operator. It is an

object of the invention to provide an improved tool operating mechanism of this type.

As illustrated in the drawings, a clutch is provided for connecting one of the tool support operating shafts on the rail with the rail moving means. Other means is provided for driving this shaft for traversing the rail independently of the drive for feeding and traversing the tool supports. Another object of the invention is to provide a novel arrangement of elements for performing these operations with convenience.

A further object of the invention is to provide mechanism in connection with the rail clamping means for feeding and traversing the tool supports from the motor when the rail is clamped and for independently operating the said one shaft therefrom for moving the rail on the uprights when the rail is unclamped, the said mechanism including means for automatically disconnecting the said one shaft from the feeding means when unclamping the rail.

With the above and other objects in view, my invention consists in the features of construction and operation set forth in the following specifications and illustrated in the accompanying drawings. In such drawings annexed hereto and forming a part of this specification, I have shown certain embodiments of my invention in a planer but it will be understood that the invention can be otherwise embodied and that the drawings are not to be construed as defining or limiting the scope of the invention, the claims appended to this specification being relied upon for that purpose.

Referring to the figures of the drawings:

Fig. 1 is a side elevation of a planer embodying my invention.

Fig. 2 is a front elevation thereof.

Fig. 3 is an enlarged front end elevation of the cross rail.

Fig. 4 is a fragmentary plan view thereof partially in section.

Fig. 5 is a fragmentary plan view of a detail shown in side elevation in Fig. 3.

Fig. 6 is an enlarged fragmentary plan view of a detail.

Fig. 7. is a plan view of the cross rail shown in Fig. 2.

Fig. 8 is a front elevation thereof.

Fig. 9 is a detail sectional view taken on

line 9—9 of Fig. 10 and showing the mechanism in the cross rail clamping position.

Fig. 10 is a plan view thereof.

Fig. 11 is a view taken on line 11—11 of

5 Fig. 12 and showing the mechanism in the cross rail unclamped position.

Fig. 12 is a plan view thereof.

Fig. 13 is a fragmentary detail view taken approximately on line 13—13 of Fig. 4.

10 Fig. 14 is an elevation of the rear end of the cross rail.

In the drawings, 1 indicates the bed of a planer having a work table 2 slidably mounted thereon and a pair of uprights 3 respectively at opposite sides of the table. A cross rail 4 is mounted to slide vertically on the uprights and is adapted to slidably support a pair of tool head saddles 5 and 6 thereon. Side head saddles 7 and 8 are respectively 15 supported on the uprights beneath the cross rail. The table 2 is adapted to be reciprocated from a motor 9 and such reciprocation is automatically controlled by a pilot switch 10 operated by table dogs 11 operating on switch arms 12. This mechanism and its operation are more fully described in Patent No. 1,299,192. The movement of the table may be controlled by means of a pendent switch 13 which is described in detail in 20 Reissue Patent No. 14,540; dated October 22, 1918.

An electric motor 14 is mounted on a rearwardly extending bracket 14' on the cross rail and, as illustrated in the drawings, this motor is adapted to feed and traverse the tool supports and to move the cross rail on the uprights. Manually operated means is provided for clamping the cross rail to the uprights. This means and the mechanism 25 cooperating with the motor for performing the said functions will now be described.

A plurality of parallel shafts 15, 16, 17, 18 and 19 are rotatably mounted on the cross rail. The screw shafts 16 and 18 are threadedly connected to the tool saddles 5 and 6 and the shaft 17 is adapted to be connected to either tool slide in the saddles in the usual manner. The screw shafts 16 and 18 are therefore respectively adapted to operate the rail saddles or heads 5 and 6 and the shaft 17 is adapted to move the tool slides vertically in the saddles.

The shaft 15 is adapted to operate the front side head 7 as follows. A bevel gear 20 on the shaft 15 is connected by means of bevel gears on a shaft 21 to a bevel gear 22 splined to the vertical front side head shaft 23. As shown in Fig. 2, the saddle 7 is supported by a nut 24 threaded to a vertical screw 25. This nut may be rotated in either direction from the shaft 23 by means of connections therebetween including bevel gears 26 loose on the shaft. Either bevel gear 26 may be connected to the shaft by means of a clutch 27 splined to the shaft and controlled

by a handle 28. The purpose of this reversing connection is to permit the feeding of the saddle 7 in either direction upon either stroke of the table 2 as will be understood.

The shaft 19 is adapted to operate the 70 back side head 8 as follows. A bevel gear 29 keyed to the rear end of the shaft 19 is in mesh with a bevel gear 30 keyed to the forward end of a short shaft 31 journaled in a bracket 32 on the rail. A spiral gear 33 75 loose on the shaft 31 is in mesh with a spiral gear 34 splined for axial movement on the back side head vertical feed shaft 35. A clutch 36 is splined to the shaft 31 rearwardly of the spiral gear 33 and a spring 37 80 normally engages the clutch with such gear, the adjacent faces of the clutch and gear being provided with cooperating clutch teeth. A bevel gear 38 splined to the vertical shaft 35 is directly connected to a nut 39 on the screw 25 which supports the side head 8 as illustrated in Fig. 2. It will of course be understood that this connection can be of the reversing type used to operate the front side head 7 if desired. 85

The means for operating the shafts 15—19 from the motor for feeding and traversing the tool supports will now be described. A pinion 40 is loosely mounted on the forward end of each of shafts 15—19 and a ratchet pinion 41 is non-rotatably and slidably mounted thereon adjacent each pinion 40. The pinions 40 and 41 are provided with cooperating clutch teeth on their adjacent faces whereby the inner non-rotatable portion of the pinion 41 may be engaged with the pinion 40. Operating handles 42 are provided for shifting the pinions 41. Two large gears 43 and 44 on a shaft 45 parallel with the shafts 15—19 are respectively 90 adapted to operate the pinions 40 and 41. The gear 43 is in mesh with the pinions 40, and the pinions 41 are adapted to be slid into meshing engagement with the gear 44. The gear 43 is adapted to be continuously 95 rotated in either direction for traversing the tool supports and the gear 44 is adapted to be intermittently rotated for feeding the tool supports, all of which mechanism is hereinafter more specifically described. 100

105 Loosely mounted on the motor shaft 46 is a worm 47 in mesh with a worm wheel 48 keyed to the shaft 45. A clutch 49 splined to the shaft 46 may be shifted into engagement with the worm 47. This clutch is 110 adapted to be shifted by an arm 50 on the rail clamping shaft 51 as hereinafter described.

The gear 43 is keyed to the shaft 45 and such gear is therefore directly connected with the motor when the clutch 49 is engaged with the worm 47. The gear 44 is loose on the shaft 45, as is also an adjacent driving member 52 therefor. The hub of the member 52 is provided with clutch teeth adapted 115

to be engaged by a clutch 53 splined to the hub of the gear 43. A spring 54 normally operates to engage the clutch with the member 52. The adjacent faces of the gear 44 and member 52 are formed with cooperating arcuate recesses for receiving compression springs 55. As thus constructed, the drive from the member 52 to the gear 44 is entirely through these springs. The arrangement is such that the springs yield sufficiently to permit a slight shock absorbing rotation of the element 52 relative to the gear 44 in both directions. This mechanism is fully illustrated and described in the said copending application.

A bushing 56 loosely mounted on the outer end of the shaft 45 has a worm wheel 57 keyed to its inner end and a dial 58 pinned to its outer end. The inner face of the worm wheel carries a stop 59 cooperating with a fixed stop 60. The gear 44 carries a stop 61 operating between the stops 59 and 60, the two latter stops being adapted to positively limit the rotation of the gear 44 in the opposite directions respectively. A shaft 62 has a worm 63 thereon in mesh with the worm wheel 57. The shaft and worm may be rotated by a handle 64 to adjust the stop 59 relative to the stop 60, the dial 58 being adapted to indicate the amount of such adjustment.

In Fig. 4, the feeding and traversing pinions 40 and 41 on the shaft 17 are shown in section and the feeding pinion 41 is shown in the neutral position. When it is desired to traverse one or more of the tool supports, the proper pinion or pinions 41 are shifted into clutching engagement with the adjacent pinions 40. A direct connection is thereby established from the motor to the tool support operating shafts 15-19.

When it is desired to feed one or more of the tool supports, the proper pinion or pinions 41 are slid into meshing engagement with the feed gear 44. The spring 54 closes the clutch 53. The pilot switch 10 which operates the motor 9 to automatically reciprocate the table 2 also controls the motor 14 as specifically defined in the before mentioned patent and copending application. Thus, as the table is reciprocated, the motor 14 rotates synchronously therewith first in one direction and then in the opposite direction. The opposite rotations of the gear 44 are limited by the stops 59 and 60 which stop the rotation of both the gear and motor. The travel of the gear is stopped positively while the springs 55 permit a slight overtravel of the motor and member 52, thus relieving the motor and its mechanism of the shock incident to the stops while at the same time securing a definite and accurate feeding movement of the gear 44. It will be understood that the pinions 41 are each provided with the usual ratchets therein for

imparting rotary movement to their shafts or screws in one or the other direction as desired.

As thus far described, it will be noted that all the tool supports may be selectively fed and traversed from the motor 14. The feeding movement of the motor and its co-operating mechanism is limited by the stops 59 and 60. Such stops positively and accurately limit the travel of the feed gear 44, while the motor and shaft 45 are permitted a slight shock-absorbing over-travel. The rotary feeding movements imparted to the shafts 15-19 and to the tool supports are therefore very definite and accurate.

The feed clutch 53 is normally closed by the spring 54. Means now to be described is provided for automatically opening this clutch when traversing (through the gear 43), such operation being necessary to prevent driving the feed gear 44. A yoke 65 mounted on a vertical pivot 66 has a rearwardly extending arm 67 engaging within the clutch groove in the clutch 53. The portion of the yoke forwardly of the pivot 66 extends vertically along the rail shifters 42'. Each clutch shifter 42' is oblong in shape and comprises a clutch shifting portion extending above its center of rotation and another portion extending below such center. The yoke has a projection 68 extending inwardly to the lower portion of each shifter (Fig. 13). When the pinions 41 are in the neutral position, illustrated in Fig. 4, or in mesh with the gear 44, the clutch 53 is engaged for feeding. Any movement of the handles 42 to engage the pinions 41 with the pinions 40, for traversing the tool supports, automatically moves the forward portion of the yoke outwardly and disengages the clutch 53. Thus the connection to the feed gear 44 is automatically disengaged whenever any tool support is being traversed.

The cross rail 4 is supported on the uprights by means of a pair of nuts 69 journaled in the rail and respectively threaded engaging the pair of screws 25 non-rotatably mounted in the uprights. The nuts are provided with worm wheels thereon engaged by worms 70 on a shaft 71 extending along the rail parallel with the shafts 15-19. The rail elevating shaft 71 is driven from the shaft 19 through a pair of spur gears 72 and 73, the gear 72 being keyed to the shaft 19 and the gear 73 being loose on the shaft 71. A clutch 74 is adapted to operatively connect the gear 73 to its shaft, a spring 75 between a collar 76 and the said clutch normally moving the clutch into engagement.

A manually operable rail clamping shaft 51 is mounted in the rail parallel with the shafts 19 and 71. This shaft carries an eccentric 77 adapted to operate on a block 78

on the inner ends of a pair of clamping levers 79. The levers are loosely bolted to the rail at 80 and the short arms thereof engage the uprights. An operating handle 81 is provided on the forward end of the clamping shaft 51. The clamping shaft is also provided with a steep pitched thread 82 thereon in engagement with a yoke collar 83 connected to the clutch 74. Rotation of the shaft 51 to clamp the cross rail to the uprights operates to withdraw the clutch to the disengaged position shown in Fig. 8. Rotation of the shaft in the direction to unclamp the rail (see arrow Fig. 3) permits the spring 75 to engage the clutch. In Figs. 1 and 3 to 10 inclusive, the mechanism is shown in the rail clamping position.

The power required to feed and traverse the tool supports is such that these operations may be performed from the large gears 43 and 44 to the pinions 40 and 41 without difficulty. However, greater power is required to elevate the cross rail and, to drive the shafts 19 and 71 for such purpose through the large gear 43 and pinion 40 would be impracticable. A separate driving connection from the motor to the shaft 19 is therefore provided for this purpose as follows.

30 A spiral gear 84 is keyed to the shaft 19 and is engaged by a spiral gear 85 loose on the motor shaft 46. The clutch 49 is provided with clutch teeth on its forward end adapted to engage with clutch teeth on the gear 85. As before stated, the clutch 49 is shifted by an arm 50 on the rail clamping shaft 51. In Fig. 4, the clamping shaft is in the rail clamping position and the clutch is engaged with the worm 47. Rotation of the clamping shaft in the rail unclamping direction will operate to shift the clutch from the worm 47 into engagement with the gear 85.

45 To provide for properly clamping the rail and shifting the clutch 49, the arm 50 is preferably loosely mounted on the clamping shaft between a pair of collars 86 and 87 pinned to the shaft as illustrated in Fig. 6. The hub of the arm is provided with a recess within which extends a projection of the collar 86, the projection being shorter circumferentially than the recess. A pair of plungers 88 and 89 are slidably mounted in the projection and normally forced outwardly by means of a spring 90. The construction is such that upon rotation of the clamping shaft a plunger will abut against its wall of the recess and resiliently engage the clutch. It will be understood that this loose connection also permits rotation of the clamping shaft to its full clamping position. It will furthermore be noted that when rotating the shaft in either direction, the mechanism positively disengages the

clutch from one element and resiliently engages the same with the other element.

5 As illustrated in Figs. 7 and 14, the rear end of the clamping shaft 51 carries an arm 91 which is connected by a link 92 to a pivoted arm 93 connected to the clutch 36. In Figs. 7 and 14, the shaft 51 is shown in the rail clamping position and the clutch is closed. When the shaft is rotated to unclamp the rail (in the direction of the arrow, Fig. 14), the connection including the link 92 will disengage the clutch. It will therefore be understood that rotation of the clamping shaft to unclamp the rail moves the clutch 49 from the worm 47 into engagement with the spiral gear 85, 80 disengages the clutch 36, and permits the engagement of the clutch 74. Conversely, rotation of the clamping shaft to clamp the rail moves the clutch 49 from the spiral gear 85 into engagement with the worm 47, 85 permits the engagement of the clutch 36, and disengages the clutch 74.

90 It has been explained that rotation of any handle 42 in a direction to engage a pinion 41 with a pinion 40, acts through the yoke 65 against the spring 54 to disengage the clutch 53. When the handle 42 is released, the spring 54 acts through the yoke and clutch shifters 42' to automatically move the clutch pinion 41 back to its neutral position. However, when the pinion 41 is shifted in the opposite direction into mesh with the gear 44, the same remains in such position until positively moved therefrom. When operating the rail traversing shaft 71 100 from the shaft 19, it is essential that the pinion 41 on the shaft 19 be in the neutral position. Should the pinion 41 be in mesh with the gear 44 when the rail is being unclamped, the clamping shaft will operate 105 through the following mechanism to automatically move such gear to the neutral position.

110 An arm 94 extends downwardly from the clamping handle 81 and a horizontal bar 95 secured to the free end of the arm extends to a position between the gears 43 and 44. A flat forwardly extending spring strip 96 is secured to the free end of the bar. This strip 115 is curved to the shape shown in Fig. 10. When the elements are in the rail clamping position (shown in Figs. 9 and 10), the free end of the strip 96 is opposite the groove 41' in the pinion 41 (the pinion being in the feeding position). The strip is also in a 120 position, as shown in Fig. 9, permitting free shifting movement of the pinion. When the clamping shaft is moved to the rail unclamping position (shown in Figs. 11 and 12), the strip enters the groove 41' and shifts the 125 pinion to the neutral position (Fig. 12). It will furthermore be noted by reference to Figs. 9 and 11 that the strip 96 is mounted

in an angular or transversely twisted position in the bar 95. In this manner, one edge *a* of the strip operates to shift the clutch to the neutral position when unclamping the 5 rail and the other edge *b* rides out of the groove and leaves the pinion in the neutral position when clamping the rail. It will be understood that the flexibility of the strip permits its riding over the pinion 41 should 10 the latter be in the neutral position when the rail is clamped instead of in the position shown in Fig. 10.

A controller 97 having an operating handle 98 is provided for operating the motor continuously in one direction or the other for traversing the tool supports or cross rail.

Briefly, the operation of my improved mechanism is as follows: The cross rail 4 being clamped, as shown in the drawings, the 20 clutch 49 is engaged with the worm 47 to operate the traversing and feeding gears 43 and 44, the back side head clutch 36 is engaged, and the rail traversing clutch 74 is disengaged. To rotate any shaft 15-19 continuously for traversing its tool support, the operator shifts the pinion 41 on such shaft into clutching engagement with the pinion 40. Such operation automatically disengages the feed clutch 53 through the yoke 65. 30 The motor 14 may now be continuously operated in either direction by the controller handle 98. To feed any tool support or supports, the proper pinions 41 are shifted into mesh with the feed gear 44. The stop 59 having been adjusted to the desired position, the gear 44 will be automatically oscillated as the work table 2 reciprocates and the tool supports will be fed the desired amount therefrom in the usual manner. The direction 40 of feed of each tool support is controlled by the usual double pawl ratchet mechanism within each ratchet pinion 41. The extent of feed of the tools is controlled by the handle 64 which adjusts the movable 45 stop 59.

When it is desired to move the cross rail on the uprights, the operator moves the clamping handle 81 in the unclamping direction (arrow, Fig. 3). This rotation of the 50 clamping shaft unclamps the rail, moves the clutch 49 from the worm 47 into engagement with the spiral gear 85, disengages the clutch 36, permits the engagement of the clutch 74, 55 and shifts the pinion 41 to its neutral position (should this pinion not already be in such position). The motor is thereby automatically connected directly to the rail elevating shaft 71, through the back side head shaft 19 and the rail may be elevated or lowered by operating the controller handle 98. The rail being adjusted to the desired 60 position, the operator moves the clamping handle 81 in the clamping direction which operation automatically clamps the rail, 65 moves the clutch 49 from the spiral gear 85

into engagement with the worm 47, permits the engagement of the clutch 36, and disengages the clutch 74. The mechanism is therefore automatically placed in the tool 70 operating position.

What I claim is:

1. In a planer or the like, the combination of an upright, a cross rail thereon, tool supports on the upright and cross rail, an electric motor, a screw on the cross rail 75 threadedly connected to the tool support thereon, a shaft on the rail parallel with the screw and operatively connected to the tool support on the upright, and means for operatively connecting the motor to the screw and shaft, the said means and motor being operative to rotate the shaft and screw continuously for traversing the tool supports or to intermittently rotate the shaft and screw optionally in one direction or the other a 80 predetermined amount for feeding the tool supports and the said means being adjustable to vary such amount.

2. In a planer or the like, the combination of an upright, a cross rail thereon, tool supports on the upright and cross rail, screw threaded means engaging each support, power means, and operative connections from the power means to the screw threaded means for feeding and traversing the supports, the said connections including mechanism on the rail for intermittently rotating the said screw threaded means a predetermined amount optionally in one direction or the other and the said means being adjustable to vary such amount.

3. In a planer or the like, the combination of an upright, a cross rail thereon, tool supports on the upright and cross rail, screw threaded means engaging each support, an electric motor on the rail, and operative connections from the motor to the screw threaded means for feeding and traversing the tool supports, the said connections including mechanism on the rail for intermittently 105 rotating the said screw threaded means a predetermined amount optionally in one direction or the other and the said means being adjustable to vary such amount.

4. In a planer or the like, the combination of an upright, a cross rail thereon, tool supports on the upright and cross rail, an electric motor, a screw on the cross rail threadedly connected to the tool support thereon, a shaft on the rail parallel with the screw and operatively connected to the tool support on the upright, a ratchet pinion on the screw, a ratchet pinion on the shaft, and power operated means on the rail operatively connected to the ratchet pinions for intermittently rotating the shaft and screw a variable predetermined amount in one direction or the other as desired.

5. In a planer or the like, the combination of an upright, a cross rail thereon, tool sup-

- ports on the upright and cross rail, an electric motor, a screw on the cross rail threadedly connected to the tool support thereon, a shaft on the rail parallel with the screw and operatively connected to the tool support on the upright, a pinion loose on the screw and a ratchet pinion adjacent thereto, a pinion loose on the shaft and a ratchet pinion adjacent thereto, and power operated means on the rail operatively connected to the pinions, the construction being such that by operating through the said loose pinions the tool supports can be continuously traversed and by operating through the ratchet pinions the tool supports can be fed intermittently in one direction or the other through a desired distance.
6. In a planer or the like, the combination of an upright, a cross rail thereon, tool supports on the upright and cross rail, an electric motor, a screw on the cross rail threadedly connected to the tool support thereon, a shaft on the rail parallel with the screw and operatively connected to the tool support on the upright, a pinion on the screw and a ratchet pinion adjacent thereto, a pinion on the shaft and a ratchet pinion adjacent thereto, a gear operatively connected with the ratchet pinions, a gear operatively connected with the other said pinions, and operative connections from the motor to the gears for optionally rotating the first gear intermittently in opposite directions a variable predetermined amount for feeding the tool supports or for rotating the second gear continuously in either direction for traversing the tool supports.
7. In a planer or the like, the combination of a pair of uprights, a cross rail thereon, tool supports on the uprights, and cross rail, an electric motor, a screw on the cross rail threadedly connected to the tool support thereon, shafting on the rail parallel with the screw and operatively connected to the tool supports on the uprights, and operative connections including ratchet pinions from the motor to the shafting and screw, the said connections being such that the tool supports may be continuously traversed and intermittently fed a variable predetermined amount from the motor.
8. In a planer or the like, the combination of a pair of uprights, a cross rail thereon, tool supports on the uprights and cross rail, an electric motor, a screw on the cross rail threadedly connected to the tool support thereon, a shaft on the rail parallel with the screw and operatively connected to one upright tool support, a second parallel shaft on the rail operatively connected to the other upright tool support, and operative connections including ratchet pinions from the motor to the shafts and screw, the said connections being such that the tool supports may be continuously traversed and inter-

mittently fed a variable predetermined amount from the motor.

9. In a planer or the like, the combination of a pair of uprights, a cross rail thereon, a tool support on the rear upright beneath the rail, a shaft on the rail operatively connected to the tool support, power means, and means providing an operative connection from the power means to the said shaft for feeding the tool support, the second mentioned means including mechanism on the front end of the rail for controlling the feeding movements of the tool support.

10. In a planer or the like, the combination of a pair of uprights, a cross rail thereon, a tool support on the rear upright beneath the rail, a shaft on the rail operatively connected to the tool support, an electric motor, and means providing operative connections from the motor to the said shaft for feeding and traversing the tool support, the said means including mechanism on the front end of the rail for controlling the feeding and traversing of the tool support.

11. In a planer or the like, the combination of a pair of uprights, a cross rail thereon, a tool support on the rear upright beneath the rail, a shaft on the rail operatively connected to the tool support, power means, and means providing an operative connection from the power means to the said shaft for feeding the tool support, the second mentioned means including mechanism on the front end of the rail for controlling the direction and extent of feeding movements of the tool support.

12. A tool operating mechanism for planers or the like comprising in combination an upright, a cross rail thereon, screw threaded means for moving the rail on the upright, means for clamping the rail to the upright, a tool support, a shaft on the rail operatively connected to the tool support, means for connecting the shaft to the said screw threaded means, an electric motor, means for operatively connecting the shaft to the motor for feeding and traversing the support, other means for operatively connecting the motor to the shaft, and means for rendering either of the last two mentioned means operative and the other inoperative.

13. A tool operating mechanism for planers or the like comprising in combination an upright, a cross rail thereon, means for moving the rail on the upright, means for clamping the rail to the upright, a tool support, a shaft on the rail operatively connected to the tool support, means for connecting the shaft to the rail moving means, power means, means for operatively connecting the shaft to the power means for feeding and traversing the support, other means for operatively connecting the power

means to the shaft, and means automatically operative to disconnect the fifth mentioned means and connect the sixth mentioned means when unclamping the rail and for connecting the fifth mentioned means and disconnecting the sixth mentioned means for clamping the rail.

14. A tool operating mechanism for planers or the like comprising in combination an upright, a cross rail thereon, screw threaded means for moving the rail on the upright, means for clamping the rail to the upright, a tool support, a shaft on the rail operatively connected to the tool support, means for connecting the shaft to the said screw threaded means, an electric motor on the rail, means for operatively connecting the shaft to the motor for feeding and traversing the support, other means for operatively connecting the motor to the shaft, and means automatically operative to disconnect the fifth mentioned means and connect the sixth mentioned means when unclamping the rail and for connecting the fifth mentioned means and disconnecting the sixth mentioned means when clamping the rail.

15. A tool operating mechanism for planers or the like comprising in combination, an upright, a cross rail thereon, screw threaded means for moving the rail on the upright, means including a manually operable clamping shaft for clamping the rail to the upright, a plurality of tool supports, a plurality of shafts on the rail each operatively connected to a tool support, means for connecting one of the shafts to the said screw threaded means, an electric motor, means including clutch means for connecting the shafts to the motor for feeding and traversing the supports, other means including clutch means for operatively connecting the motor to the said one shaft, and means operated by the clamping shaft for shifting the clutch means to connect the motor with the means for operating the shafts for feeding and traversing when clamping the rail and for shifting the clutch means to connect the motor with the said one shaft when unclamping the rail.

16. A tool operating mechanism for planers or the like comprising in combination, an upright, a cross rail thereon, means for moving the rail on the upright, means for clamping the rail to the upright, a plurality of tool supports, a plurality of shafts on the rail each operatively connected to a tool support, means for connecting one of the shafts to the rail moving means, power means, mechanism intermediate the shafts and power means for feeding and traversing the supports, a driving element on the said one shaft, and means operated by the clamping means for automatically connecting the power means to the said

mechanism when clamping the rail and for disconnecting the same and connecting the power means to the said driving element when unclamping the rail.

17. A tool operating mechanism for planers or the like comprising in combination, an upright, a cross rail thereon, means for moving the rail on the upright, means for clamping the rail to the upright, a plurality of tool supports, a plurality of shafts on the rail each operatively connected to a tool support, means for connecting one of the shafts to the rail moving means, power means, mechanism intermediate the shafts and power means for feeding and traversing the supports, a driving element on the said one shaft, a clutch for optionally connecting the power means either to the said mechanism or to the said driving element, and means operated by the clamping means for shifting the clutch to connect the power means to the said mechanism when clamping the rail and for connecting the power means with the said driving element when unclamping the rail.

18. A tool operating mechanism for planers or the like comprising in combination, an upright, a cross rail thereon, means for moving the rail on the upright, means for clamping the rail to the upright, a plurality of tool supports, a plurality of shafts on the rail each operatively connected to a tool support, means including a clutch for connecting one of the shafts to the rail moving means, power means, mechanism intermediate the shafts and power means for feeding and traversing the supports, a driving element on the said one shaft, and means operated by the clamping means for connecting the power means to the said driving element and for closing the said clutch when unclamping the rail and for disconnecting both such connections and connecting the power means with the said mechanism when clamping the rail.

19. A tool operating mechanism for planers or the like comprising in combination, an upright, a cross rail thereon, means for moving the rail on the upright, a tool support, a shaft on the rail operatively connected to the support, means for connecting the shaft to the rail moving means, a motor on the rail, mechanism intermediate the motor shaft and rail shaft for operating the rail shaft to feed and traverse the support, a gear on the rail shaft, a clutch on the motor shaft for optionally connecting either the said gear or mechanism to the motor shaft, and means for shifting the clutch.

20. A tool operating mechanism for planers or the like comprising in combination, an upright, a cross rail thereon, means for moving the rail on the upright, means for clamping the rail to the upright, a tool

- support, a shaft on the rail operatively connected to the support, means for connecting the shaft to the rail moving means, a motor on the rail, mechanism intermediate the motor shaft and rail shaft for operating the rail shaft to feed and traverse the support, a gear on the rail shaft, a clutch on the motor shaft for optionally connecting either the said gear or mechanism to the motor shaft, and means operated by the clamping means for shifting the clutch to connect the motor to the said mechanism when clamping the rail and for connecting the motor to the said gear when unclamping the rail.
21. A tool operating mechanism for planers or the like comprising in combination, an upright, a cross rail thereon, means for moving the rail on the upright, means for clamping the rail to the upright, a tool support, a shaft on the rail operatively connected to the support, means providing a disengageable connection between the shaft and the rail moving means, a motor, mechanism intermediate the motor shaft and rail shaft for operating the rail shaft to feed and traverse the support, a gear on the rail shaft, clutch means for optionally connecting either the said gear or mechanism to the motor, and means operated by the clamping means for shifting the said clutch means to connect the motor to the said mechanism when clamping the rail and for connecting the motor to the said gear when unclamping the rail.
22. A tool operating mechanism for planers or the like comprising in combination, a pair of uprights, a cross rail thereon, screw threaded means for moving the rail on the upright, means for clamping the rails to the uprights, a plurality of tool supports, a plurality of shafts on the rail each operatively connected to a tool support, means for connecting one of the shafts to the said screw threaded means, power means, means on the rail for operatively connecting the shafts to the power means for feeding and traversing the supports, other means for operatively connecting the power means to the said one shaft, and means automatically operative to disconnect the fifth mentioned means and connect the sixth mentioned means when unclamping the rail and for connecting the fifth mentioned means and disconnecting the sixth mentioned means when clamping the rail.
23. A tool operating mechanism for planers or the like comprising in combination, a pair of uprights, a cross rail thereon, screw threaded means for moving the rail on the uprights, means for clamping the rail to the uprights, a plurality of tool supports, a plurality of shafts on the rail each operatively connected to a tool support, one of the shafts being connected to a tool support on one of the uprights, means for connecting

the said one shaft to the screw threaded means, an electric motor, means for operatively connecting the shafts to the motor for feeding and traversing the supports, a clutch for connecting the motor to the said one shaft, and means automatically operative to disconnect the fifth mentioned means and engage the clutch when unclamping the rail and for connecting the fifth mentioned means and disengaging the clutch when clamping the rail.

24. In a planer or the like, the combination of an upright, a cross rail thereon, means for moving the rail on the upright, means including a manually operable clamping shaft for clamping the rail to the upright, a tool support, a shaft on the rail for operating the tool support, disengageable means for connecting the shaft to the rail moving means, power means, disengageable means including a feed gear for operatively connecting the shaft to the power means for feeding the support, other disengageable means for operatively connecting the power means to the shaft, and means automatically operated by the clamping shaft to disconnect the said one shaft from the feed gear when clamping the rail.

25. In a planer or the like, the combination of an upright, a cross rail thereon, means for moving the rail on the upright, means for clamping the rail to the upright, a plurality of tool supports, a plurality of shafts on the rail for respectively operating the tool supports, disengageable means for connecting one of said shafts to the said screw threaded means, power means, disengageable means including clutch means on each of said shafts for operatively connecting the shafts to the power means for feeding and traversing the supports, other disengageable means for operatively connecting the power means to the said one shaft, and means automatically operative to shift the said clutch means on the said one shaft to a neutral position when unclamping the rail.

26. In a planer or the like, the combination of an upright, a cross rail thereon, means for moving the rail on the upright, means for clamping the rail to the upright, a tool support, a shaft on the rail for operating the tool support, means for connecting the shaft to the rail moving means, power means, means including a feed gear for operatively connecting the shaft to the power means for feeding the support, other means including a gear on the shaft for operatively connecting the power means to the shaft, means automatically operative to disconnect the fifth mentioned means and connect the sixth mentioned means when unclamping the rail and for connecting the fifth mentioned means and disconnecting the sixth mentioned means when clamping the rail, and means automatically operative to dis-

connect the said one shaft from the feed gear when unclamping the rail.

27. In a planer or the like, the combination of an upright, a cross rail thereon, means for moving the rail on the upright, means for clamping the rail to the upright, a plurality of tool supports, a plurality of shafts on the rail for respectively operating the tool supports, means for connecting one of said shafts to the rail moving means, power means, means including clutch means on each of said shafts for operatively connecting the shafts to the power means for feeding and traversing the supports, other means for operatively connecting the power means to the said one shaft, means automatically operative to disconnect the fifth mentioned means and connect the sixth mentioned means when unclamping the rail and for connecting the fifth mentioned means and disconnecting the sixth mentioned means when clamping the rail, and means automatically operative to shift the ratchet pinion on the said one shaft to a neutral position when unclamping the rail.

28. In a planer or the like, the combination of an upright, a cross rail thereon, means for moving the rail on the upright, means for clamping the rail to the upright, a plurality of tool supports, a plurality of shafts on the rail for respectively operating the tool supports, means for connecting one of said shafts to the rail moving means, power means, means including a ratchet pinion on each shaft for operatively connecting the shafts to the power means for feeding the supports, other means for operatively connecting the power means to the said one shaft, means automatically operative to disconnect the fifth mentioned means and connect the sixth mentioned means when unclamping the rail and for connecting the fifth mentioned means and disconnecting the sixth mentioned means when clamping the rail, and means automatically operative to shift the ratchet pinion on the said one shaft to a neutral position when unclamping the rail.

29. In a planer or the like, the combination of an upright, a cross rail thereon, screw threaded means for moving the rail on the

upright, means including a clamping shaft for clamping the rail on the upright, a plurality of tool supports, a plurality of shafts on the rail for respectively operating the tool supports, means for connecting one of said shafts to the said screw threaded means, power means, means including a ratchet pinion and an adjacent pinion on each shaft for operatively connecting the shafts to the power means for feeding and traversing the supports, other means for operatively connecting the power means to the said one shaft, means automatically operative to disconnect the fifth mentioned means and connect the sixth mentioned means when unclamping the rail and for connecting the fifth mentioned means and disconnecting the sixth mentioned means when clamping the rail, and means automatically operative to 70 shift the ratchet pinion on the said one shaft to a neutral position when unclamping the rail.

30. In a planer or the like, the combination of an upright, a cross rail thereon, screw threaded means for moving the rail on the upright, means for clamping the rail to the upright, a plurality of tool supports, a plurality of shafts on the rail for respectively operating the tool supports, means for connecting one of said shafts to the said screw threaded means, power means, means including clutch means on each of said shafts for operatively connecting the shafts to the power means for feeding and traversing the supports, other means for operatively connecting the power means to the said one shaft, means automatically operative to disconnect the fifth mentioned means and connect the said other connecting means when unclamping the rail and for connecting the fifth mentioned means and disconnecting the said other connecting means when clamping the rail, means automatically operative to shift the said clutch means on the said one shaft to a neutral position when unclamping the rail, and means for respectively connecting and disconnecting the third mentioned means when unclamping and clamping the rail.

In testimony whereof, I hereto affix my signature.

HARRY LITTLE.
